UNITED STATES PATENT OFFICE

MARTIN LEBEIS, OF BERLIN, GERMANY, ASSIGNOR TO REMINGTON RAND INCORPORATED, OF NEW YORK, N. Y., A CORPORATION OF DELAWARE

TABULATING MACHINE

Application filed October 23, 1929, Serial No. 401,832, and in Germany October 9, 1925.

This invention relates to tabulating machines of the kind that are controlled by a previously prepared record, which record usually consists of a perforated card.

5 The invention has for its principal object to extend the capacity of the machine so that a much larger amount of data can be tabulated from a card of given size and with a given spacing of perforations than has been 10 possible heretofore. The invention is shown applied to a Powers tabulator which, as heretofore constructed, has usually comprised sensing pins arranged in 45 rows of 12 pins each, and each card has been adapted to receive 15 perforations in 45 rows, space being provided for perforation in any one or more of 12 different positions in each row. By a comparatively slight modification this same machine, with the same number of sensing 20 pins disposed in the same way and adapted to use the same size card as heretofore, has its capacity doubled so that data can be tabulated in 90 denominational positions instead of in 45 as heretofore. This result is 25 effected by causing each row of 12 spaces to take care of two numerals or digits instead of one as heretofore and by providing additional tabulating units in the head of the machine.

30 To the above and other ends which will hereinafter appear, the invention consists in certain combinations and arrangements of parts and in certain details of construction all of which will be fully set forth herein and 35 particularly pointed out in the claims.

An illustrative embodiment of the invention is described hereinafter and illustrated in the accompanying drawings.

Fig. 1 is a diagrammatical illustration of 40 an accounting unit of a tabulator;

Fig. 2 shows a portion of the punched card for use in the tabulator of Fig. 1.

The invention is shown applied to an ordinary Powers tabulator which, except for 45 the changes hereinafter described, may be constructed and operated as usual. The machine is of the general construction shown in patents to Powers Nos. 1,245,502 of Nov. 6, 1917 and 1,245,504 of Nov. 6, 1917.

50 The feeler pins 18, carried by pin box 19

reciprocated in timed relation with the rest of the mechanism, operate as analyzers for the punched card 21 in the well known manner. This card is one of a series which may be fed between the plates 20 in sequence by 55 mechanism which is shown in the above patents.

At each operation of the pin box 19, certain rods 10 or 15 slidably arranged in stationary plates 16 and 17 will be operated according to the punchings in the cards to set the adding and printing head of the machine. The rods 10 or 15 are therefore adapted to be lifted under the control of the card-perforations.

I divide the card 21 longitudinally by an imaginary line into two zones and in each up and down row of 12 spaces I use the upper six spaces to indicate one digit or numeral and the lower six spaces to indicate another digit 70 or numeral. The setting of the ten types for printing and also the setting of the gear rack for adding is in each instance controlled by six spaces on the card. In order to accomplish this it is of course, in some instances, necessary to punch two holes in one row to represent a digit. As shown in Fig. 1 only six of the rods 15 go to one denominational position and the other six rods 10 in the same row may go to another denominational position. 75 Each denominational position of the tabulating mechanism is thus controlled by only six rods 10 or 15. This can be accomplished in a variety of ways of which one is illustrated in the drawing.

80 Five of the rods 15 of a given denomination act on five setting members 120 which are mounted for easy movement in the direction of alignment of the stops in a shiftable frame 121. Each tabulator denomination is equipped with one such frame. The frames are guided on rods 122 by means of short slots 123 and are equipped with pins 124, engaging curved slots 125 of arms 126. These arms may be operated by special selector pins 127. The slot 125 is so shaped 85 as to shift the frame 121 to the left with reference to Fig. 1 in the beginning of the movement of its arm 126.

The setting members 120 are equipped at 90

their lower ends with enlarged feet adapted to be engaged by the selector pins 15 when the frame is moved to the left. With the arm 126 in the position illustrated in Fig. 1, 5 the setting members 120 operate those stop members 14 only, which are designed with the reference numerals 1, 3, 5, 7 and 9. If arm 126 is lifted, the frame 121 is so moved to the left as to bring the setting members 10 120 in cooperative position with the stop members 14 bearing the numerals 0, 2, 4, 6 and 8. It may or may not move out of the range of stops 1, 3, 5, 7 and 9. The arm 126 may be lifted by means of a selector 127 and 15 means are provided to cause the latter to lift the arm 126 at the beginning of its upward movement for shifting the frame 121 to the left before the other selectors 15 engage the setting members 120.

20 All of the arms 126 are positively restored by a rod 128 which is moved in unison with the analyzer pin-box 19 in the same manner as the restoring bars 75.

The selector pins 10 pass in an oblique direction to a second unit of the machine behind the one shown. By this arrangement a single column of perforations in a card may be used to operate two, ten element units in the adding head. The mechanism described 25 is controlled by punched cards provided with special perforations.

In Fig. 2 a portion of such a card is shown. The reference numerals 0 to 9 at the sides denote the data represented by the perforations 22 or 21 in the respective columns. The punched card is divided in two fields 40 and 41, each of which accommodates the record of 30 one digit for each column.

The registering, adding, printing and accumulating mechanism is of standard construction similar to that indicated in Patents 1,039,130 of Sept. 24, 1912 and 1,209,817 of Dec. 26, 1916.

The sides 11 carried by base 12 support 45 sector shaft 23. This shaft loosely carries a plurality of adding rack sectors 66 and printing sectors 25. The sector 66 is tensioned to operate to the right through the action of spring 26 acting on arm 27 integral with sector 25, when released by bail 29 carried by 50 bail operating arms 30 mounted on shaft 23. Printing is accomplished by hammers 34 striking a type of sector 25 and driving it against the platen 28 on which is arranged a record sheet therefor.

A slot and pin connection 31, 32 permits play between the sectors 25 and 66 in a well known manner and the spring 45 permits the movement of sector 25 with relation to sector 66. These parts are well known and are operated in timed relation to the other parts above mentioned by means disclosed in the above patents.

60 By the present arrangement it is only necessary to replace the stop and stop car-

riages of the above patents with stop pins and their operating mechanism as above set forth to produce the result desired.

The operation is as follows:

It may be assumed that the digit 7 is to 70 be recorded. As it will appear from the drawings, the fourth selector from the left is to be raised in this instance. Upon a short lost-motion stroke this selector engages the opposite setting member 120, thereby lifting the stop member 7 to operative position in which it will cause the printing and totalizing unit, in a well-known manner, to register the digit 7. If the digit 6 is to be registered, the selector 127 is lifted by providing suitable perforations in the card in addition to the fourth selector 15 from the left. This raises the arm 126, shifting the frame 121 to the left by action of the curved slot 125 before the fourth selector 15 actuates its 75 setting member 120. As soon as the frame has been shifted, the selector 15 engages the setting member 120, thereby raising the stop member 14 bearing the numeral 6 into operative position.

It will be apparent that the frame 121 need not be shifted a larger distance than is necessary to lift the member 14 of next lower order. This will be the member 6 in this instance, while it is immaterial whether or 80 not the adjacent member of next higher order, as for instance, the member 7, is carried along together with the actuated member because the abutment 65 on sector 66 will strike stop 6 before it will strike stop 7. The registration of the digit 6 is accomplished in the usual manner. When the stop members 14 are restored by the bars 75, the arm 126 is likewise returned to its normal position by action of the rod 128.

From this construction it may be seen that the ten stops of the adding head may be operated from six stops in the analyzer.

Having thus described my invention in what I believe its best form I desire that the disclosure be considered for purposes of illustration only and not in a limiting sense, it being possible to substitute known structures for equivalent elements herein described.

What I desire to claim is:—

1. In a machine of the class described, a registering mechanism, setting means therefore consisting of one or more units of aligned stops, setting members for said means mounted for movement in the direction of alignment of said stops, a card analyzer for individually actuating said setting members both in a sliding direction and collectively in the direction of alignment of said stops.

2. In a machine of the class described, a card analyzer unit, a registering mechanism actuated thereby, said analyzer unit having longitudinally movable members and means

for automatically shifting connections between said members and said mechanism.

3. In a machine of the class described, a card analyzer unit having a plurality of longitudinally movable elements, a registering mechanism actuated thereby, including stops operated by said elements and shiftable means for connecting certain of said stops to said elements.

10 4. In a machine of the class described, a card analyzer unit having a plurality of longitudinally movable elements, a registering mechanism actuated thereby including stops operated by said elements, certain of said stops being normally disconnected from said elements and shiftable means for connecting said certain stops with said elements.

20 5. In a machine of the class described, a card analyzer unit having a plurality of longitudinally movable elements, a registering mechanism actuated thereby including stops operated by said elements, certain of said stops being normally disconnected from said elements and shiftable means for connecting said certain stops with said elements upon longitudinal movement of one of said elements.

30 6. In a machine of the class described, a card analyzer unit having a plurality of longitudinally movable elements, a registering mechanism actuated thereby including stops operated by said elements and shiftable means for connecting certain of said stops to said elements upon longitudinal movement of one of said elements.

35 7. In a machine of the class described, a card analyzer unit having a plurality of longitudinally movable elements, a registering mechanism actuated thereby including a number of stops not connected to said elements in said analyzer and shiftable means for connecting said disconnected stops to said analyzer.

40 8. In a machine of the class described, a card analyzer unit having a plurality of longitudinally movable elements, a registering mechanism actuated thereby including a number of stops not connected to said elements in said analyzer and shiftable means for connecting said disconnected stops to said analyzer having an operator connected to one of said elements.

45 9. In a machine of the class described, a card analyzer unit having a plurality of longitudinally movable elements, a registering mechanism actuated thereby including a number of stops not connected to said elements in said analyzer and shiftable means for connecting said disconnected stops to said analyzer and disconnecting any stops normally connected to said analyzer.

50 10. In a tabulator, an analyzer having pins, stops actuated thereby, a register controlled by said stops, and an interconnecting device between said stops and pins for causing

certain of said stops to be actuated by said pins only when said interconnecting device is operated.

11. In a tabulator, an analyzer having pins, stops actuated thereby, a register controlled by said stops, an interconnecting device between said stops and pins for causing certain of said stops to be actuated by said pins only when said interconnecting device is operated, and operating connections between said analyzer and interconnecting device.

75 12. In a tabulator, a card analyzer having pins, stops actuated thereby, a register controlled by said stops and interconnecting elements disposed between said pins and stops, mounted on a movable carriage, one end of each of said elements being enlarged to cooperate with one of said pins in any position of said carriage within its range of movement.

80 13. In a tabulator, a card analyzer having pins, stops actuated thereby, a register controlled by said stops, interconnecting elements disposed between said pins and stops, mounted on a movable carriage, one end of each of said elements being enlarged to cooperate with one of said pins in any position of said carriage within its range of movement and means for moving said carriage including one of said pins.

85 14. In a tabulator, a card analyzer having pins, stops actuated thereby, a register controlled by said stops, interconnecting elements disposed between said pins and stops, mounted on a movable carriage, one end of each of said elements being enlarged to cooperate with one of said pins in any position of said carriage within its range of movement and means for moving said carriage including one of said pins, the other end of said elements arranged to actuate more than one stop depending upon the position of said carriage.

90 15. In a tabulator, a card analyzer having pins, stops actuated thereby, a register controlled by said stops, interconnecting elements mounted on a movable carriage disposed between said pins and stops, means for moving said carriage including one of said pins, said means being operable before the operation of said stops by said pins.

100 16. In a tabulator, a card analyzer having pins, stops actuated thereby, a register controlled by said stops, interconnecting elements mounted on a movable carriage for interchangeably connecting said pins with different ones of said stops, and actuating means for said interconnecting elements.

110 17. In a tabulator, a card analyzer having pins, stops actuated thereby, a register controlled by said stops, interconnecting elements mounted on a movable carriage for interchangeably connecting said pins with different ones of said stops, and actuating means

for said interconnecting elements prior to the normal operation of the stops by others of said pins.

18. In a tabulator, a card analyzer having pins, stops actuated thereby, a register controlled by said stops, interconnecting elements mounted on a movable carriage for interchangeably connecting said pins with different ones of said stops, said pins being arranged with lost motion between their ends and said elements, one of said pins connected to actuate said carriage without lost motion.

Signed at Berlin, Germany, this 7th day of October, A. D. 1929.
